(57) **CLAIM**

We claim the ornamental design for a weight bench cushion arrangement, as shown and described.

DESCRIPTION

FIG. 1 is a perspective view of a weight bench cushion arrangement;

FIG. 2 is a top view of a weight bench cushion arrangement;

FIG. 3 is a side view of a weight bench cushion arrangement; and,

FIG. 4 is a rear view of a weight bench cushion arrangement.

The broken line showing of weight bench is included for the purpose of illustrating environmental structure and forms no part of the claimed design.
